(57) CLAIM

The ornamental design for a cosmetic organizer as shown and described.

DESCRIPTION

FIG. 1 is a perspective view of a cosmetic organizer showing my new design;

FIG. 2 is an exploded perspective view thereof; and, FIG. 3 is another exploded perspective view thereof. The broken lines in the figures are for the purpose of illustrating portions of the cosmetic organizer, which form no part of the claimed design.

1 Claim, 3 Drawing Sheets

FIG.2
